UNITED STATES PATENT OFFICE.

LA FAYETTE H. ROBINSON, OF GRINDSTONE, NEW YORK.

NAPKIN-HOLDER.

993,408.

Specification of Letters Patent. Patented May 30, 1911.

Application filed October 6, 1909. Serial No. 521,295.

To all whom it may concern:

Be it known that I, LA FAYETTE H. ROBINSON, of Grindstone, in the county of Jefferson, in the State of New York, have invented new and useful Improvements in Napkin-Holders, of which the following, taken in connection with the accompanying drawings, is a full, clear, and exact description.

10 This invention relates to certain improvements in napkin holders for temporarily fastening table napkins and similar articles to the waist, coat, or other garments and comprises a pair of pin supporting sections, 15 hinged together, and adapted to be folded into compact space ready for use when desired.

The main object is to provide a simple and comparatively inexpensive fastener, 20 which may be folded into a small space and carried in the pocket to protect the pin points from being bent or being caught on the lining of the pocket.

A further object is to arrange the pins in 25 such manner that they may be easily and expeditiously hooked into the garment and napkin, and as readily detached when desired.

Other objects and uses relating to the 30 specific parts and their relative arrangement will be brought out in the following description:

In the drawings: Figure 1 is a perspective view of a portion of a garment and 35 napkin, showing my improved fastener in operative position. Figs. 2 and 3 are perspective views of the same fastener, shown in its open and partially closed positions, respectively. Fig. 4 is a side elevation of 40 the same device, in its folded position, ready to be inserted in the pocket. Fig. 5 is a transverse sectional view, taken on line 5-5, Fig. 2.

This fastener consists of two comparatively thin and narrow sheet metal bars 45 —1— and —2—, hinged together end to end, by a suitable pintle —3— and adapted to be folded, one upon the other, in the manner shown in Fig. 4, or may be unfolded to the positions shown in Figs. 1 and 2. The free ends of the leaves or bars are bent inwardly in the same direction or toward each other when folded forming protective shoulders —4—.

55 Secured to the inner faces of the bars —1— and —2—, near the ends thereof are

suitable hooks or fastening pins, which are, in this instance, bent intermediate their ends in the same direction forming base portions —6— and point portions —7— and constituting what may be termed hooked shaped fasteners. The opposite arms of these points extend in the direction of length of the bars to which they are secured, substantially midway between the 60 edges thereof, the base portions —6— of each fastener being secured by any suitable fastening means to the inner face of the corresponding bar and in the construction shown, one end of the base portion —6— is 65 passed through an aperture —8— in the corresponding bar some distance from the free end thereof and riveted thereto, while the opposite end of said base is passed through a loop —9— which, in this instance 70 is made in the form of a staple, secured to the bar near the junction of the arms —6— and —7—.

The apex or point of junction of the arms —6— and —7— preferably butts against or 75 lies in close proximity to the adjacent shoulder —4—, so as to additionally retain the fastener in place, the said fastener being held against turning laterally by the lateral offset which passes through the aperture 80 —8—, thus causing the pin points or arms —7— to stand out some distance away from the arm and to point toward each other when the bars are unfolded for use, as 85 shown in Figs. 1 and 2.

90 This construction of napkin holder is particularly advantageous and effective by reason of the fact that it is reversible thus permitting either end to be attached to a garment as —a— and the other end to a 95 napkin as —b—.

The pointed ends —7— are located wholly within the sides and ends of the bars to which they are secured and, although substantially central longitudinal, they are 100 offset just sufficient to enable them to slide past one another when the bars are folded in the manner shown in Fig. 4, so as to permit the bars to be folded close together. In 105 this folded position the pin points lie wholly between the bars and project toward the hinged connection where they are protected from contact with the lining of the pocket or fingers and also against being bent by such contact; and at the same time the shoulders —4—, on the free ends of the 110 bars serve to additionally protect the pins

against contact with other objects which may be carried in the same pocket with the fastening device.

In placing the napkin holder in position for use, it is simply necessary to unfold it and to press one pin down into the garment —*a*— and thus draw the edge of the napkin into engagement with the other point, as shown in Fig. 1, whereupon the weight of the napkin or any tendency to displace the latter downwardly, operates to further grip the pins in their respective parts.

What I claim is:

A napkin holder comprising two flat rectangular bars having their opposing ends hinged together and each having its free end provided with an inwardly-extending flange, each of said bars having its interme-

diate portion provided with apertures, means to provide an inwardly extending loop secured in certain of the apertures of each of the bars, and headed pins projecting through the other apertures of said bars and extending through and around said loops, abutting against said flanges and having their free ends projecting toward the hinge of the bars, said pins positioned at the longitudinal center of the inner face of said bars.

In witness whereof I have hereunto set my hand on this 25th day of September 1909.

LA FAYETTE H. ROBINSON.
